UNITED STATES PATENT OFFICE

98,086

DESIGN FOR A SHOWCASE

Frank L. Pollard, Oakland, Calif.

Application October 25, 1935, Serial No. 59,214

Term of patent 3½ years

To all whom it may concern:

Be it known that I, Frank L. Pollard, a citizen of the United States, residing at Oakland, in the county of Alameda and State of California, have invented a new, original, and ornamental Design for a Show-Case, of which the following is a specification, reference being had to the accompanying drawing, forming part thereof.

I claim:

The ornamental design for a show-case as shown.

FRANK L. POLLARD.
